CLAIM

The ornamental design for a vacuum for a wood or coal stove or fireplace ash, as shown and described.

DESCRIPTION

FIG. 1 is a front elevational view of the vacuum for a wood or coal stove or fireplace ash showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

FIGS. 1, 2, 5 and 6 are shown broken away to show indeterminate length.

FIG. 1

FIG. 2

FIG. 3

FIG. 4

FIG. 5

FIG. 6
